UNITED STATES PATENT OFFICE.

HORACE E. SWIFT, OF BOSTON, MASSACHUSETTS, ASSIGNOR TO THE JONES-SWIFT MANUFACTURING COMPANY, OF PORTLAND, MAINE.

COMPUTING BEAM-SCALE.

SPECIFICATION forming part of Letters Patent No. 552,676, dated January 7, 1896.

Application filed March 19, 1895. Serial No. 542,340. (No model.)

To all whom it may concern:

Be it known that I, HORACE E. SWIFT, of Boston, county of Suffolk, State of Massachusetts, have invented an Improvement in Computing Beam-Scales, of which the following description, in connection with the accompanying drawings, is a specification, like letters and numerals on the drawings representing like parts.

10 This invention has for its object the production of a computing beam-scale of simple and durable construction, whereby the movement of the poise upon the usual beam will indicate the weight, computing mechanism to indicate the aggregate price of the article weighed according to a given price, being operable proportionally to the movement of the poise, a manually-operated controlling member determining by its angularity the extent of movement of the computing mechanism.

In accordance therewith my invention consists, in a computing beam-scale, of a weighing member including a beam, and a poise movable thereon, computing mechanism proportionally to the movement of the poise, a controlling member to determine by its angular position the extent of movement of said computing mechanism, and means to manually fix and maintain the angularity of said controlling member, substantially as will be described.

Other features of my invention will be hereinafter described, and particularly pointed out in the claims.

35 Figure 1, in elevation, represents one form of beam-scale embodying my invention. Fig. 2 is an enlarged view in elevation of the overhanging arm of the scale with the front plate removed to show the operating parts. Fig. 3 is a vertical section on the irregular line a^x , Fig. 2, looking toward the left; and Fig. 4 is a perspective view of a detail to be described.

Referring to Fig. 1, the base A, standard A', platform B, graduated beam B' fulcrumed at 40 5, and the connecting-link B² between the beam and the platform-supports are and may be of any usual and well-known construction.

The standard A' has secured thereto by a bracket a, Figs. 2 and 3, an overhanging arm 50 a', preferably grooved longitudinally in its front side at a², Fig. 3, to receive a rib b^x on a

back plate b provided with a projecting wall or flange b', straight at its ends and a portion of the top, and circularly curved at b², Figs. 1 and 3, the said curved portion being provided with an inturned ledge b³, upon which a dial rests and is secured, as by suitable screws 6. A front plate a^x is secured to the flange b' and extended across the arm, the bottom of the front plate being slightly higher than the bottom of the back plate for a purpose to be described. A horizontal guide-rod c is rigidly secured to the end walls b' behind the front plate, Fig. 3, and a slide-block c', (shown separately in Fig. 4,) movable longitudinally on the rod c, is provided with a rearwardly-extended foot c², upon which is rigidly mounted a post c³, loosely surrounded by a movable collar c⁴. The collar c⁴ has pivoted thereon at c⁵ a slotted or grooved block d, in engagement with a controlling member d'. (Shown in Fig. 2 as an arm pivoted at d² to the back plate b in the plane of the guide-rod c and connected at its base end by a pin or stud d³ to one end of a lever d⁴ fulcrumed at d⁵.)

A hollow sleeve e, Figs. 2 and 3, is rotatable in bearings in the dial D and in a bracket e^x, and has secured to it behind the dial a plate e' having an evolute periphery, and a bevel-gear e², in mesh with a similar gear e³ fast on a shaft e⁴, mounted in a bearing e⁵ and extended through the curved wall b², its outer end having fast thereon a suitable milled or other nut e⁶, whereby the evolute e' may be rotated in one or the other direction. Guides d⁶ on the back plate receive a slide-rod d⁷, bent over, as at d⁸, to bear against the edge of the evolute e', and pivoted at its lower end to the lever d⁴. Obviously, rotation of the evolute e' in the direction of the arrow 20, Fig. 2, will depress the slide-rod d⁷, turning the lever d⁴ on its fulcrum, and by raising its free end increasing the angularity of the controlling member d' relative to the guide-rod c, opposite rotation of the evolute decreasing the angularity of said member, which is inoperative when parallel to the guide-rod. The weight of the long arm of the lever d⁴, the controlling member d' and the parts resting thereon is sufficient to turn said lever on its pivot to elevate the slide-rod d⁷ and keep it in engagement with the evolute plate,

though it will be obvious that if desired a spring could be attached to the slide-rod to aid in elevating it.

The evolute, its rotating devices and the connections between the evolute and the controlling member d' constitute manually-operated means to fix or adjust the angularity of the latter. The angularity of the member d' controls the vertical movement of the collar c^4 on the post c^3 through the block d , according to the extent of lateral movement of the block c' longitudinally on the guide-rod c , for it is evident that unless the member d' is parallel to the guide-rod c the collar c^4 will be raised higher the more nearly the slide-block c' approaches the right-hand end thereof, viewing Fig. 2. A bar f , pivotally supported on like links f' to rise and fall in parallelism with the guide-rod, rests on a projecting pin c^6 on the collar c^4 , to be raised or lowered by vertical movement of the latter. The foot of a vertically-movable rack g bears on the top of the bar f , the rack-teeth meshing with a pinion g' fast on a spindle g^2 stepped in a bearing g^3 on the back plate b and extended loosely through and beyond the sleeve e , a hand or pointer G , Fig. 1, secured to the spindle co-operating with a scale G' on the face of the dial denoting dollars and cents, said hand being moved through an angular distance proportional to the throw of the rack g . The rack g having a variable throw, and the connections between it and the indicating hand or pointer G constitute computing mechanism, it being evident that the higher the collar c^4 is moved the greater will be the throw of the rack g , and its hand G' will sweep over a larger arc on the dial.

A hand or pointer E is secured to the outer end of the sleeve e to co-operate with a scale E' on the dial-face, and herein shown as numbered from zero to 99, though any other numbering may be used as desired.

The slide-block c' projects beneath the front plate a^8 (see Fig. 3) and has thereon an upturned lug c^7 , (clearly shown in Figs. 3 and 4,) having a vertical side 10 and preferably an inclined side 12, ears c^{10} and c^{12} being pivoted to said lug adjacent its sides, as shown in Fig. 1 and partially in Figs. 3 and 4. The ears are normally separated by suitable springs s , Fig. 3 and 4, that spring controlling the ear c^{12} being preferably harder than the other, so that when compressed the ear c^{10} will be more easily brought against the vertical side 10 first.

The poise B^X , movable longitudinally on the graduated beam B' in well-known manner, has a depending finger 30 thereon, one side being in the vertical place of the indicating side of the poise, said finger preferably extending between the ears c^{10} and c^{12} , but out of engagement at all times with the lug c^7 .

When it is desired to weigh and compute the aggregate price of an article for a given unit price, the operator preferably grasps the ears, moving ear c^{10} against the vertical side

10 of the lug c^7 , holding the finger 30 between the ears, and the poise is moved along the beam B' until the weight of the article is indicated on the beam. The finger 30 is held in alignment with the vertical side 10 of the lug by the finger-piece c^{10} , and the block c' is moved a corresponding distance on the guide-rod c . Either before or afterward the thumb-nut e^6 is turned to bring the hand E opposite the given unit price, thereby fixing the angularity of the controlling member d' , and so determining the vertical movement of the collar c^4 on the post c^3 for every increment of weight indicated by the poise B^X on the beam. If this is done before operating the computing mechanism, movement of the latter will cause a simultaneous sweep of the hand or pointer G over its scale, so that the price of the article will be computed on the dial as the movement is effected. Inasmuch as the throw of the rack g depends on the extent of vertical movement imparted to the bar f by the collar c^4 , and as such movement of the latter is determined by the angularity of the controlling member, it will be obvious that the controlling member governs or determines the movement of the computing mechanism.

The various parts are so adjusted that the computing mechanism will compute and indicate the aggregate cost of any article weighed, for a given unit price, within the limits of the scale.

If the article is first weighed and then the angularity of the controlling member fixed, the result will be the same, the computed cost being at once indicated on the dial, the hand G moving thereon simultaneously with the adjustment of the controlling member.

It will be observed that the movement of the computing mechanism is due to the resultant of the horizontal and vertical movements imparted to the collar c^4 , and the scale is consequently what may be termed a "right-line computing-scale."

My invention is not restricted to the precise construction and arrangement herein shown and described, for, so far as I am aware, it is broadly new to determine the movement of the computing mechanism of a beam-scale by the angularity of a controlling member manually operated according to the unit price of the article weighed and maintained in fixed position.

I prefer, for the sake of convenience and rapidity of operation, to actuate the computing mechanism simultaneously with the movement of the poise on the beam; but it will be obvious that the poise may be moved on the beam and the computing mechanism independently operated proportionally to such movement, so that my invention is not restricted to a movement of the computing mechanism by the poise.

I claim—

1. In a computing beam scale, a weighing member, including a beam and a poise movable thereon; computing mechanism operable,

proportionally to the movement of the poise; a controlling member to determine by its angular position the extent of movement of said computing mechanism; and means to manually fix and maintain the angularity of the controlling member, substantially as described.

2. In a computing beam scale, a weighing member, including a beam, and a poise movable thereon; computing mechanism; connections between it and the poise, to operate said mechanism by movement of the poise on the beam; a controlling member co-operating with said connections, to determine by its angular position the movement of the computing mechanism; and means to manually fix and maintain the angularity of said member according to the unit price, substantially as described.

20 3. In a computing beam scale, a graduated beam and a poise movable thereon; a dial provided with a price indicating scale, and a pointer movable thereon; computing mechanism to move said pointer; a controlling member to determine by its position the movement of said mechanism; means adjustable according to the unit price to fix and maintain the position of the controlling member, and normally disconnected means intermediate the poise and computing mechanism, to operate the latter, substantially as described.

25 4. In a computing beam scale, a weighing member, including a beam and a poise movable thereon; computing mechanism; a pivoted controlling member to determine by its angular position the movement of said mechanism; connections intermediate the poise and the computing mechanism, in operative engagement with said controlling member, and 40 means to manually move said member on its pivot and thereby fix and maintain its angularity according to the unit price, substantially as described.

30 5. In a computing beam scale, a weighing member, including a beam and a poise movable thereon; computing mechanism; connections intermediate said mechanism and poise, including a member movable in a right line path proportionally to the movement of the poise; a controlling arm to determine by its angular position the movement of said member at right angles to its said path, whereby the computing mechanism is operated by the resultant movement of said members; and 50 means to manually fix and maintain the angularity of said controlling arm, substantially as described.

6. In a computing beam scale, a beam and a poise movable thereon; computing mechanism, including a rack having a variable throw, 60 connections between said rack and the poise, operated by adjustment of the poise, to throw the rack; a pivoted controlling member in engagement with said connections and to determine by its angular position the throw of said 65 rack; and means to manually fix and maintain the angular position of said controlling member, substantially as described.

7. In a computing beam scale, a graduated beam and a poise movable thereon; a slide 70 block movable in a plane parallel to the beam and adapted to be moved proportionally to the movement of the poise; a fixed guide for said block; a collar mounted on and adapted to be moved at right angles to the path of the 75 slide block; computing mechanism operable by movement of said collar; a manually adjustable controlling member to determine by its position the movement of the collar relative to the slide block, whereby the computing mechanism will be moved in accordance with the adjustment of the poise and the controlling member, substantially as described.

8. In a computing beam scale, a graduated beam and a poise movable thereon; computing mechanism operable by adjustment of the poise; a controlling member to determine by its angular position the movement of said mechanism; and means to fix and maintain the position of said member, including a rotatable plate having an evolute periphery and connections intermediate it and the controlling member, substantially as described.

9. In a computing beam scale, a graduated beam and a poise movable thereon; a dial 95 having unit and computed-price scales thereon; pointers co-operatively movable thereon; computing mechanism operable by adjustment of the poise, to actuate the computed price pointer; a pivoted controlling member 100 to determine by its angularity the movement of said computing mechanism; and means to manually fix and maintain the angular position of said controlling member and simultaneously actuate the unit-price pointer, substantially as described.

In testimony whereof I have signed my name to this specification in the presence of two subscribing witnesses.
